Roy Glanvill, Kensington, London, and Peter James Wise, Bristol, England; said Wise assignor to said Glanvill

Application July 27, 1953, Serial No. 26,159

Term of patent 14 years

(Cl. D9—2)

To all whom it may concern:

Be it known that we, Roy Glanvill and Peter James Wise, both citizens of the United Kingdom of Great Britain and Northern Ireland, respectively residing at Kensington, London, England, and Bristol 3, England, have invented a new, original, and ornamental Design for a Head for a Toilet Bowl Brush or the like, of which the following is a specification, reference being had to the accompanying drawing, forming part thereof.

Fig. 1 is a front perspective view of a head for a toilet bowl brush or the like, showing our new design;

Fig. 2 is a rear perspective view;
Fig. 3 is a bottom plan view; and
Fig. 4 is a rear elevational view thereof.

We claim:

The ornamental design for a head for a toilet bowl brush or the like, as shown.
